PROCESS OF AND APPARATUS FOR SEPARATING MIXED MATERIALS

Walter L. Remick, Hazleton, Pa., assignor to
Hydrotator Company, Cleveland, Ohio, a corporation of Delaware

Application August 15, 1931, Serial No. 557,417

5 Claims. (Cl. 209—157)

My invention consists in a new and useful improvement in process of and apparatus for the separation of mixed materials and is designed for separating materials of different specific gravity, 5 and particularly for the treatment of ore to separate it from other materials with which it is mixed. My improved process consists of two steps: (1st) wherein the finer particles of light material are removed by hydraulic classification, 10 leaving a mixture of (a) coarse particles of heavy material, (b) coarse particles of light material, and (c) fine particles of heavy material; (2nd) wherein the fine particles of heavy material (c in the first step) are used to build up a high 15 density classifying medium whereby the coarse particles of light material (b in the first step) may be floated from the coarse particles of heavy material (a in the first step) and subsequently separated from the fine particles of heavy material by screening.

While I have hereinafter fully described my improved process and one specific embodiment of my improved apparatus as fully illustrated in the drawings filed herewith, it is to be distinctly 25 understood that I do not consider my invention limited to this specific embodiment and its operation, but refer for the scope of my invention of both process and apparatus to the claims appended hereto.

30 In the drawings:

Fig. 1 is a side elevation of my apparatus.

Fig. 2 is a top plan view.

Fig. 3 is a section on line 3—3 of Fig. 1.

To perform the initial step in my improved 35 process, I make use of the classifying apparatus described and claimed in United States Letters Patent Number 1,767,227, granted to me on June 24, 1930. This apparatus has the liquid-containing tank 1 having suitably mounted thereover the supporting frame 2 from which depends the rotatable pipe 3 extending into the tank 1 and received about the upper end of the pipe 4 which passes through the bottom of the tank 1. Extending laterally from the pipe 3 adjacent the 40 bottom of the tank 1 there is a series of pipes 5 in communication with the pipe 3 and provided with downwardly projecting tangentially disposed nozzles 6.

Suitably mounted upon the frame 2 there is the 45 motor M having the downwardly extending shaft 7 suitably journaled in the bearing 8 provided in the spider 9 mounted at a suitable point in the pipe 3 and forming a guide for the liquid passing through pipe 3 and providing a constricted throat 50. The shaft 7 is provided upon its lower end

with impeller blades 11, and the pipe 3 is provided at a suitable point between the top of the tank 1 and the plane of the blades 11 with a series of openings 12. The tank 1 is provided with an overflow launder 13 with a discharge opening 14. 60 I provide any suitable form of chute C for supplying the materials to the tank 1. The tank 1 has at its bottom the discharge pipe 15, with the control valve 16, over the sluice S.

To perform the subsequent step in my improved 65 process, by treating the product flowing from the discharge pipe 15, I provide a concentrator such as is described and claimed in United States Letters Patent Number 1,511,643, having the tank 17 under the sluice S, with an overflow launder 18 70 having the discharge opening 19. Suitably positioned above the tank 17, I provide any suitable form of support 20 for the rotatable shaft 21 upon the lower end of which and suitably disposed in the tank 17 is the five-way head 22 75 carrying four distributing pipes 23 having thereon depending nozzles 24 disposed at an angle to the bottom 25 of the tank 17. The lower end of the head 22 has the depending pipe 26 engaged over the upper end of the inlet pipe 27 extending upwardly through the bottom 25 of the tank 17. To this pipe 27 there is connected the discharge 80 side of the pump P, and I provide a check valve, as at V, between the pump P and the inlet pipe 27, so arranged as to permit flow of liquid from the pump P to the interior of the tank 17 and prevent escape of liquid from the tank 17 through pipe 27 when the pump P is not in operation. I provide any suitable means for driving the pump P, as a motor M—1. I provide a sump 28 85 connected with the intake side of the pump P. I provide a hopper H suitably supported over the sump 28 so as to discharge thereinto. It is to be noted that the sump 28 has an inclined baffle plate 29, the lower edge 30 of which is spaced a short distance from the discharge of sump 28 to the pump P and the upper edge 31 of which is spaced a short distance from the discharge opening of the hopper H. I provide an over-flow 90 opening 32 for sump 28.

I provide an inclined shaker screen 33 suitably supported above the hopper H and below the discharge opening 19 of tank 17 and having the pulley 34 which may be driven by any suitable means (not shown) for shaking the screen 105 33.

Suitably disposed adjacent the bottom 25 of the tank 17, I provide a discharge chute 35 leading from the interior of the tank 17 to the bottom of the scraper elevator 36 and having the 110

slide valve 37 with its control rod 38. The elevator 36 has its lower shaft 39 provided with a pulley 40 which may be driven by any suitable means (not shown) for operating the elevator 5 36. The upper discharge end 41 of the elevator 36 may be supplied with any suitable form of means (not shown) for carrying off the product delivered by the elevator 36. It is to be noted (Fig. 1) that the upper discharge end 41 of the 10 elevator 36 is at a height considerably above the top of the tank 17, and at a point somewhat above the level of the top of the tank 17, I provide the elevator 36 with a discharge sluice S—1 which permits the liquid carried up in the elevator 15 36 to drain back into the tank 17.

From the foregoing description of the details of construction of my improved apparatus, its operation in the practice of my improved process will be obvious. The tank 1 is filled with water 20 through the pipe 4. The mixed materials, as for instance iron ore mixed with its associated materials as mined, are run into tank 1 by the chute C. The hydraulic classification performed by my construction in tank 1 causes the slimes 25 of lighter material to discharge from the top of the tank 1 through the launder 13 and its overflow 14, while the particles of ore, both fine and coarse, are deposited on the bottom of the tank 1, with such of the coarse particles of the light 30 material as have not been overflowed. This accumulation is discharged from the tank 1 through the pipe 15 and sluice S into tank 17 which has been filled with water from any suitable source of supply. The operation of the concentrating process in tank 17 causes the coarse 35 heavy particles of ore to deposit on the bottom 25 of the tank 17, and the coarse light particles of the other material, with the fine particles of ore, to overflow tank 17 through the launder 18 40 and from the discharge opening 19 pass over the shaker screen 33. The coarse light particles are discharged to waste, while the fine particles of ore pass with the water through the screen 33, and hopper H, into the sump 28 and are re- 45 turned to the tank 17 by circulating through the pump P. Thus it will be seen that I provide for building up the density of the liquid in the tank 17 by circulating the fine particles of ore, therein, thus materially increasing the specific gravity 50 of the concentrating liquid medium, and thereby assuring a more complete separation of the particles of ore from the particles of lighter material.

When a sufficient quantity of ore has become deposited on the bottom 25 of the tank 17, the 55 valve 37 may be opened by its control rod 38, thereby permitting the ore to be discharged from the tank 17 through the chute 35 into the elevator 36, by which it is elevated to be discharged from the tank 17 at the upper end 41 of the elevator 36, as the 60 product of my improved process.

It is to be noted that such of the liquid medium as is carried up from the discharge chute 35 by the scraper elevator 36 to a point above 65 the level of the top of the tank 17 will escape from the elevator 36 by the sluice S—1 and return thereby to the tank 17 carrying with it such of the particles of fine ore as may be held in suspension in the liquid.

70 Having described my invention, what I claim is:

1. The process of separating mixed materials which consists in subjecting the materials to the

effect of an upwardly flowing current of liquid thereby, removing from the mixture the fine particles of the lighter material, removing the mixture of fine and coarse particles of the heavy material and the coarse particles of the light material from said current, subjecting said mixture to hydraulic concentration in a liquid medium; removing the mixture of coarse particles of the light material and the fine particles of the heavy material from the liquid medium; separating the fine particles of the heavy material from the coarse particles of the light material, returning the fine particles of the heavy material to the liquid medium, and removing the accumulated particles of the heavy material from the liquid medium.

80 2. The process of separating ore from its associated material which consists in subjecting the mixture to the effect of an upwardly flowing current of liquid thereby removing the slimes, removing the mixture of coarse and fine particles of ore and coarse particles of the associated material from said current, subjecting said mixture to the action of a concentrating liquid medium, increasing the density of said medium by 95 concentration of the fine particles of ore therein, removing the coarse particles of the associated material, and removing the accumulated ore.

90 3. The process of separating mixed materials 105 which consists in subjecting the materials to the effect of an upwardly flowing current of liquid thereby removing from the mixture the fine particles of the lighter material, removing the mixture of fine and coarse particles of the heavy 110 material and the coarse particles of the light material from said current, subjecting said mixture to hydraulic concentration by the circulation of a liquid medium, recovering from said medium the coarse particles of the light material, maintaining the circulation of only the fine particles 115 of the heavy material, and recovering from said medium an accumulation of the particles of the heavy material.

120 4. The process of separating ore from its associated material which consists in subjecting the mixture to the effect of an upwardly flowing current of liquid thereby removing the slimes, removing the mixture of coarse and fine particles of ore and coarse particles of the associated material from said current, subjecting said mixture to the concentrating action of a circulating fluid medium, recovering from said medium the coarse 125 particles of the associated material, maintaining the circulation of only the fine particles of ore, 130 and recovering from said medium an accumulation of ore.

135 5. In an apparatus for separating mixed materials, the combination of a tank for a liquid medium; means in said tank adapted to circulate the liquid medium through said tank; an overflow launder at the top of said tank; a shaker screen under said overflow launder; a hopper under said screen; a sump under said hopper and in communication with the said circulating means 140 of said tank; a discharge chute from the bottom of said tank; an elevator from said chute, having its upper discharge end elevated considerably above the said launder; and a sluice leading out of the casing of the elevator, discharging into said 145 tank at a point directly above the top of said tank.

WALTER L. REMICK.
